(57) **CLAIM**

I claim the design for an automobile rear bumper hitch and protector, as illustrated in the figures described herein.

DESCRIPTION

FIG. 1 is a view of the bumper hitch and guard as seen from directly behind the automobile (not illustrated).

FIG. 2 is a view of the bumper hitch and guard as seen from above.

FIG. 3 is a view of the bumper hitch and guard as seen from below.

FIG. 4 is a view of the bumper hitch and guard as seen from the right side where right side refers to the right side of the automobile (not illustrated); and,

FIG. 5 is a perspective view of the bumper hitch and guard as seen from above and to the right.
